BULLET

Walter L. Keller, Philadelphia, Pa., and George A. Miller, Jr., Weirsdale, Fla.

Application June 2, 1949, Serial No. 96,804

1 Claim. (Cl. 102—90)

(Granted under Title 35, U. S. Code (1952),
sec. 266)

1

The invention described in the specification and claim may be manufactured and used by or for the Government for governmental purposes without the payment to us of any royalty thereon.

This invention relates to small arms bullets in general, and, in particular, to bullets which include a hard core, a jacket and a sabot-like cup as integral components thereof.

Broadly stated, the object of this invention is to provide a bullet comprising the abovementioned components, among other things, which components will not become disassociated upon being fired from a rifled firearm.

A more specific object is to provide such a bullet whose jacket will not become stripped therefrom upon being fired from a rifled firearm.

Another specific object is to provide such a bullet whose sabot-like cup will not become stripped therefrom upon being fired from a rifled firearm.

A further object is to provide such a bullet whose jacket and sabot-like cup will tend to tighten to each other and to the bullet's core, rather than loosen, when the bullet is fired.

A still further object is to provide such a bullet which can be adapted for armor piercing, armor piercing-incendiary, or armor piercing-incendiary-tracer usage.

One embodiment of the present invention is illustrated in the accompanying drawings, wherein:

Fig. 1 is a side elevation view of an ammunition round incorporating our novel bullet, portions of the cartridge case having been broken away to show conventional case components with which our bullet may be combined; and

Fig. 2 is a similar view of the bullet shown in Fig. 1, portions of the bullet having been broken away to show beneath the outer jacket: the core, the sabot-like base cup, and the manner of attachment of these three components to each other.

Referring to the drawings it will be seen from Fig. 1 that our inventive bullet 10 may conventionally be assembled in a cartridge case 11 and secured thereto by crimping the case, as at 12, into the bullet jacket's cannelure 13. The cartridge case may be filled behind the bullet with a propellant powder charge 14 that is ignitable by a primer 15.

From Fig. 2 it will be seen that our illustrative novel bullet is formed from a jacket 20, a core 21, base cup 22 and incendiary powder 23. The base cup 22 is first assembled onto the reduced diam-

2

etered shank 24 of core 21 and secured thereto by applying a cannelure 25 which crimps the cup wall into the circumferential groove 26 provided therefor in the exterior of the core shank 24.

5 The core and base cup sub-assembly is then forced into jacket 20, as shown, until a rim 27 on the closed or base end of cup 22 is in flush contact with the mouth end 28 of the jacket. In order to make the thus assembled components a tight-fitting unit, the internal diameter of the mouth end of jacket 20 is selectively dimensioned to be slightly smaller than the external diameter of base cup 22. As a result, insertion of the core-cup sub-assembly in the jacket causes the jacket's mouth end to swell along the depth that the cup penetrated thereinto. After such insertion, cannelure 13 is applied to secure the jacket to the base cup, preferably in the same region as the cup's cannelure 25 (as shown).

10 The thus assembled bullet is a unit of desired components which are inseparable throughout the bullet's flight notwithstanding the severe forces exerted thereon. Instead of the components tending to disassociate themselves, the tendency is for them to tighten their grips on each other. The normal predisposition towards stripping which the jacket possesses is overcome by virtue of its being crimped (cannelure 13) to base cup 22. Similarly, the base cup cannot be 15 pulled out of the jacket's mouth end because the same crimp or cannelure 13 acts to lock the jacket and base cup, and thus overcome this type of stripping tendency. In like fashion, the core 21 is secured to the base cup 22 and in turn to jacket 20. When the bullet is fired, the riflings of the gun (not shown) cause counterpart riflings (not shown) to be engraved on the exterior base wall of the jacket in the region which has been swollen by insertion of the base cup. The grooves 20 of these riflings serve further to crimp the jacket 20 and base cup 22 together. These crimps, together with the initial canneluring crimps, aid in preventing disassociation of the bullet parts during the bullet's entire propulsion in the direction of the target.

15 By our present design, as will be obvious to those skilled in the art, the gas-tight seal and the provision of a suitable surface for taking the gun's rifling are both accomplished without the danger of either the jacket or the sabot stripping from the bullet. The rim 27 of the sabot-like base cup 22 completely covers the mouth end 28 of jacket 20 and thus effects a gas-tight seal so that no gas seeps in between the base cup and 20 the jacket, the gas which propels the bullet

merely striking the closed end of the base cup. Air cannot get in between the cup rim 27 and the jacket 20 as the two are in flush-tight fitting relationship. Because air cannot get therebetween, and further because the cup and jacket are held together by the cannelure crimp 13 the two are inseparable notwithstanding the severe centrifugal force exerted thereon. Furthermore and most important, since the base cup is made to swell the rear end of the jacket to a size large enough to receive the riflings of the gun (not shown) through which it may be fired, the full benefit which the art knows to be derived from the use of rotating bands or sabots can now be attained without the danger of the sabot stripping from the bullet and fouling the gun.

As will be obvious, our inventive improvements are usable in bullets of various calibers and types such as armor piercing, armor piercing-incendiary, and armor piercing-incendiary-tracer.

From the foregoing it will be seen that we have provided a bullet comprising a jacket and sabot-like cup as integral components thereof, which component will not become disassociated upon being fired from a rifled firearm; that we have provided a bullet whose jacket will not become stripped therefrom upon being fired from a rifled firearm, that we have provided a bullet whose sabot-like cup will not become stripped therefrom upon being fired from a rifled firearm; that we have provided such a bullet whose jacket and sabot-like cup will tend to tighten to each other and to the bullet's core, rather than loosen, when the bullet is fired; and that we have provided such a bullet which can be adapted for armor-piercing, armor piercing-incendiary, or armor piercing-incendiary-tracer usage.

Accordingly, our invention is broad in its adaption and is not to be restricted to the specific form here shown and described by way of illustration.

We claim:

In a bullet of the type described, a metallic generally cylindrical core having an ogival nose, square-cut rearward end and a rearward portion of reduced diameter forming a rearwardly-facing annular shoulder approximately midway between the ends of said core, there being a cannelure in said reduced portion, a base cup having an external diameter slightly larger than the main forward portion of said core and a square-cut rearward end enlarged to form an external rim defining a forwardly-facing annular shoulder, said cup fitting snugly about the reduced rearward end of said core and having its forward edge abutting the annular shoulder thereof and a cannelure overlying the cannelure in said core, and a thin-walled metallic jacket fitting snugly about said cup and core, said jacket having an ogival nose and a square-cut rear end abutting the forwardly-facing shoulder on said cup, said jacket and cup being crimped into the cannelures in said cup and core, respectively, that portion of said jacket overlying said cup being expanded thereby to form a driving band section, there being a space defined between the ogival noses of said core and jacket.
